United States Patent Office

Des. 224,449
Patented July 25, 1972

224,449

FILM CUTTER

Thomas C. Laughon, Rochester, N.Y., assignor to Eastman Kodak Company, Rochester, N.Y.

Filed Mar. 15, 1971, Ser. No. 124,641

Term of patent 14 years

Int. Cl. D16—99

U.S. Cl. D61—1

FIG. 1

FIG. 2

FIG. 3

FIG. 1 is a top left rear perspective view of a film cutter showing my new design;

FIG. 2 is a right side elevational view thereof; and FIG. 3 is a top left front perspective view thereof.

I claim:

The ornamental design for a film cutter, as shown.
